BINDER FOR LOOSE LEAF BOOKS

Thomas E. Heeter, St. Louis, Mo.

Application February 12, 1936, Serial No. 63,485

10 Claims. (Cl. 129—12)

This invention relates to improvements in binders for loose leaf books.

An object of the invention is to provide, in a binder for loose leaf books, means for adjustment of one cover of the book relative to the other that may be easily operated, together with a locking device for locking the adjustable cover in selected positions.

Another object of the invention is to provide, in a construction of the class mentioned, a locking device that may be readily adjusted to accommodate it to various spacings of the posts upon which the book leaves are mounted.

Additional advantages of the construction will be apparent from the following detailed description thereof, taken in connection with the accompanying drawings in which

Fig. 1 is a plan view of the binder.

Fig. 2 is an edge view.

Fig. 3 is an enlarged sectional view showing the details of the locking mechanism.

Fig. 4 is a vertical section taken substantially on the line 4—4 of Fig. 3.

Fig. 5 is a detail view of the locking lever and the associated adjusting nut cooperating therewith.

Fig. 6 is a view similar to Fig. 3 with the construction shown in unlocked position.

Fig. 7 is a vertical section substantially on the line 7—7 of Fig. 6.

Fig. 8 is a vertical section taken substantially on the line 8—8 of Fig. 3.

Fig. 9 is a vertical section on the line 9—9 of Fig. 3.

Fig. 10 is a section on the line 10—10 of Fig. 3.

Fig. 11 is a disassembled view of parts of the locking mechanism in reverse position.

Fig. 12 is a disassembled detail view of the locking plate.

A construction of the present invention is embodied in a book binder which comprises a lower tube 1 having rigidly secured thereto spaced posts 2. The posts are in the form of rods, the ends of which extend through openings in the tube

45 and are riveted in position by rivet heads 3 in order to provide a rigid connection between the tube and posts. Spaced along the inner edge of the tube 1 and connected therewith are hinge straps 4 that cooperate with a hinge member 5

50 and a hinge pin 6 to form a hinge connection between the tube 1 and the lower cover 7 of the book, the hinge being of the type commonly known as a piano hinge.

The posts 2 that upstand from the tube 1 are made of the desired length to accommodate the

leaves 8 of the book, it being understood that the leaves are connected with the pins by the usual slot and hole connection. The upper cover of the book is connected to the posts 2 so that its elevation in respect to the cover 7 may be adjusted to accommodate a leaf stack of different thicknesses and the upper cover is made removable so that the leaves may be assembled with the posts 2 and removed therefrom by slipping the leaves over the tops of the posts. It will be understood that, for the purpose of removal and for the purpose of adjustment of the elevation of the top cover, it is necessary to associate the connecting means for the top cover with the posts in such a way that the cover may be locked at different elevations to the posts and may be unlocked for removal and adjustment.

It is particularly with this construction that the present invention is concerned. The means connecting the top cover with the posts includes a tube 9 having spaced openings 10 therein adapted to generally register with and fit over the posts 2. The top cover 11 of the book is connected to the tube 9 by a hinge connection of the same construction as the hinge connection between the lower cover of the book and the lower tube, comprising the hinge straps 4, the hinge member 5 and the hinge pin 6.

The lock construction is mounted within the tube 9 and comprises a bracket associated with each post, said bracket including a bottom plate 12 having an oblong opening 13 therein with upstanding lugs 14 at each end. Mounted within each bracket is a locking plate 15, said locking plate having an irregularly shaped opening, the wider cross dimension of the opening at one end being slightly larger than the diameter of the posts and at the narrowest end having a cross diameter substantially that of the diameter of the posts. This locking plate is pivoted at one 40 of its longitudinal edges between the lugs 14 of the bracket. The means for pivoting the locking plate in the bracket comprise forming in the spaced lugs 14 at one corner of each thereof an inclined slit 16 and seating in said slits the ears 45 17 formed integral with one edge of the plate 15. The free edge of the locking plate 15 is held normally in a downwardly inclined position by means of a U-shaped spring 18, one end of which is connected with the locking plate 15 by inserting the 50 extremity of the spring 18 in an opening 19 in the plate. The opposite arm of the spring is seated in the bracket. This construction provides means for resiliently holding the locking plate in inclined position.

By reference to Figs. 3 and 6, the former of which shows the locking plates in locking adjustment, and the latter of which shows the locking plates in unlocked adjustment, it will be understood that, by sliding the brackets longitudinally of the tube 9, the locking plates may be brought into frictional engagement with the posts 2, as shown in Fig. 3, and out of frictional engagement with the posts 2, as shown in Fig. 6, by alternately encircling the posts by the narrow and wider portions of the openings in the locking plates. The pivoted relationship of the locking plates with the brackets permits the movement of the locking plates into frictional contact with the posts and prevents the locking plates from wedging against the throat between the narrower and wider portions of the openings in said plates. When the throats of these openings in the plates are moved against the posts, the slight tilting action permits the movement and then the frictional engagement of the narrower portions of the openings against the perimeter of the posts.

The means for moving the brackets to locked and unlocked positions include pull rods 20, which pull rods have hooks 21 at one end and threaded portions 22 at their opposite ends. The hooks 21 fit in ears 23 formed integral with the inner end lugs 14 of the brackets. The threaded portions of the rods 20 pass through threaded openings 24, respectively, in a nut 25.

It will be understood that it is necessary, in order that the locking position of each of the locking plates with its respective post shall be accurately adjusted so that the locking plates are in a position to lock both posts simultaneously, that the spacing between the brackets by which the locking plates are carried shall be accurate. In other words, both locking plates must come to a finely adjusted position in order that the lock may efficiently operate. This fine adjustment is accomplished by the threaded adjustment between the rods 20 and the nut 25. The nut 25 has upstanding from its base spaced lugs 26 forming a seat or channel therebetween that extends transversely of the tube.

The mechanism is actuated by means of a lever which includes a cam arm 27, which arm is seated in the channel between the lugs 26 and is mounted in the tube for rocking motion by inserting a deflected end 28 of the cam arm in an opening in the outer wall of the tube 9 and passing the forward deflected end 29 of the cam arm through a bushing 30 supported in an opening in the inner edge of the tube 9.

A handle including an arm 31 and a deflected portion 32 serves to throw the cam arm 27 and act as a detent to hold the device in locked position, as will be understood by reference to Figs. 3 and 10 in which the deflected portion 32 is shown as snapped over the edge of one of the hinge straps carried by the tube.

To unlock the device the arm 31 is thrown backwardly, as illustrated in Fig. 6, which movement causes the brackets to slide longitudinally in the tube 9 to bring the wide diameter in the openings in the locking plates in registration with the posts 2. In this position it will be understood that the tube 9 and thereby the top cover of the book may be moved vertically of the posts 2 either for the purpose of removal therefrom or for predetermining the elevation thereof.

In order to summarize the operation of the construction, it will be understood that, in adjusting the top cover of the book, the lever or

handle 31 is thrown to the position shown in Fig. 6. This releases the posts from impingement by the locking plates and permits the tube 9 to be freely moved on the posts. When the selected distance of the tube 9 from the tube 1 is determined, the lever handle 31 is thrown to the position shown particularly in Figs. 3 and 10, the movement causing the brackets to move longitudinally of the tube 9 and, as the openings in the locking plates move from the wider to the narrower diameter, the locking plates rise slightly toward a horizontal position and, after the posts have passed the throats in the openings of the locking plates, the springs tend to depress the free ends of the locking plates, causing them to tightly impinge against the perimeters of the posts 2 and prevent their movement in respect thereto.

It is thus seen that a construction is provided that may be readily operated, that may be cheaply constructed, and that will efficiently perform its function of locking and unlocking the connection with the upper cover of the binder to the posts that support the pages of the book.

I claim:

1. In a loose leaf book binder, the combination with a lower tube pivotally supporting a bottom book cover, and spaced leaf supporting posts rigidly carried by said lower tube, of an adjustable upper tube pivotally supporting an upper book cover and slidably mounted on said posts, sliding lock plate carriers within said upper tube, locking plates pivotally carried by said carriers and having slots therein, each of said slots having a wide portion of greater diameter than the diameter of the posts, and a narrow portion tightly fitting a respective one of said posts, and manually operable means for simultaneously moving said carriers to engage and disengage said narrow portions of the slots in said locking plates with said posts.

2. In a loose leaf book binder, the combination with a lower tube pivotally supporting a bottom book cover, and spaced leaf supporting posts rigid with and upstanding from said bottom tube, of an adjustable upper tube pivotally supporting an upper book cover and having openings therethrough for sliding engagement of said upper tube with said posts, lock plate carriers longitudinally movable in said upper tube, locking plates each having a keyhole slot therein carried by said carriers, said plates being adapted to be in engagement with said posts when the narrow portions of the keyhole slots are about the posts and to be in disengagement with the posts when the wide portions of the keyhole slots are about the posts, an adjustable connection between said carriers, and means associated with said connection for manually simultaneously moving said carriers to engage and disengage said locking plates with said posts.

3. In a loose leaf book binder, the combination with a lower tube pivotally supporting a bottom book cover, and spaced leaf supporting posts rigid with and upstanding from said bottom tube, of an adjustable upper tube pivotally supporting an upper book cover and having openings therethrough for sliding engagement of said upper tube with said posts, lock plate carriers longitudinally movable in said upper tube, locking plates carried by said carriers and adapted to engage and disengage said posts, a connection between said carriers including tie rods and a nut threaded to said tie rods for adjusting the length of said connection, a slot in said nut,

and a cam device having a portion in contact with said slot, said cam device being manually operable for moving said connection and thereby said carriers to lock and unlock the locking plates with said posts.

5 4. In a loose leaf book binder, the combination with a lower tube pivotally supporting a bottom book cover, and spaced leaf supporting posts rigid with and upstanding from said bottom tube, of an adjustable upper tube pivotally supporting an upper book cover and having openings therethrough for sliding engagement of said upper tube with said posts, lock plate carriers longitudinally movable in said upper tube, locking plates carried by said carriers and adapted to engage and disengage said posts, tie rods constituting a connection between said carriers, a nut threaded to said tie rods for adjusting the length of said connection, a slot in said 10 nut, a cam arm operable in said slot to move said connection and thereby said carriers to engage and disengage the locking plates carried by said carrier, and an integral arm extending from said cam arm for manual manipulation 15 thereof.

20 5. In a loose leaf book binder, the combination with a lower tube pivotally supporting a bottom book cover, and spaced leaf supporting posts rigid with and upstanding from said bottom tube, of an adjustable upper tube pivotally supporting an upper book cover and having openings therethrough for sliding engagement of said upper tube with said posts, lock plate carriers longitudinally movable in said upper tube, locking plates carried by said carriers and adapted to engage and disengage said posts, tie rods constituting a connection between said carriers, a nut threaded to said tie rods for adjusting the length of said connection, a slot in said nut, a 25 cam arm operable in said slot to move said connection and thereby said carriers to engage and disengage the locking plates carried by said carrier, an integral arm extending from said cam arm for manual manipulation thereof, and a latch device for holding the arm against movement when the same has been moved to a position to lock said locking plates with said posts.

30 6. In a loose leaf book binder, the combination with a lower tube pivotally supporting a bottom book cover, and spaced leaf supporting posts upstanding from and rigidly connected with said lower tube, of an adjustable upper tube having openings therein through which said posts extend, said tube being slidable with respect to said posts, lock devices for locking and unlocking said upper tube to said posts, said lock devices including carriers slidable in said upper tube and locking plates in said carriers, each of 35 said locking plates being pivoted for movement at one longitudinal edge thereof and each having

a keyhole type slot therein for engaging and disengaging a respective one of said posts, and means for moving said carriers.

40 7. In a loose leaf book binder, the combination with a lower tube pivotally supporting a bottom book cover, and spaced leaf supporting posts upstanding from and rigidly connected with said lower tube, of an adjustable upper tube having openings therein through which said posts extend, said tube being slidable with respect to 45 said posts, lock devices for locking and unlocking said upper tube to said posts, said lock devices including carriers slidable in said upper tube and locking plates in said carriers, each of said locking plates being pivoted for movement 50 at one longitudinal edge thereof and each having a keyhole type slot therein for engaging and disengaging a respective one of said posts, and springs associated with said plates for normally actuating said plates towards said carriers.

55 8. A loose leaf binder comprising a lower cover supporting tube, spaced leaf supporting posts connected to and extending from said lower tube, an upper cover supporting tube having holes therethrough for sliding engagement with the 60 posts, and means for adjustably fixing said upper tube on said posts in selective positions relative to said lower tube, said means including spring urged plates mounted in said upper tube, each having a keyhole slot therein surrounding a respective post, and means for moving said plates simultaneously bodily longitudinally of the upper tube to alternately bind and release said posts.

65 9. Locking mechanism for loose leaf binders comprising brackets, a locking plate pivotally connected to each bracket and spring urged towards its respective bracket, each plate including a keyhole slot, and adjustable means connecting said brackets.

70 10. A loose leaf binder comprising upper and lower cover supporting means, loose leaf supporting posts connected to and extending from the lower supporting means, said upper supporting means comprising a tube having spaced holes therethrough to allow said tube to slide along said 75 posts, and locking mechanism within said tube for holding said tube in selective positions on said posts including a movable bracket associated with each post, a plate pivoted to each bracket and surrounding the associated post by means of 80 a keyhole slot, means connecting said brackets, and means for moving said brackets simultaneously through said connecting means to alternately engage and disengage said posts by the narrow portions of the keyhole slots, said plates 85 being spring pressed into frictional engagement with said posts in the said engaging position of the locking mechanism.

THOMAS E. HEETER. 60
